UNITED STATES PATENT OFFICE

2,442,246

STEREOTYPE CASTING MACHINE

Wayne O. Peterson, Moorhead, Minn.

Application October 15, 1945, Serial No. 622,284

4 Claims. (Cl. 22—5)

1

My invention relates to type casting machines and more particularly to the type known in this art as "stereotype casting boxes."

In machines of this type a casting platten comprising upper and lower superimposed plates are used. These plates are generally hinged together at their forward ends and the lower plate is mounted on horizontally disposed opposed rails secured to the inner sides of a frame structure for limited compound sliding and tilting movements. Such movements are necessary when pouring stereotype metal into the mold.

When it is desired to cast an impression with machines of this type, it is essential that the lower plate first be in a horizontal position and the upper plate raised on its hinges to a substantially vertical position so that the work can be laid out on the smooth surface of the lower plate. The matrix is then placed in a central position on the face of the lower plate, the closure forming strips or bars placed about the three sides of the matrix, leaving the rear end open, and a cover paper placed over the closure strips. The upper plate is then lowered into position so as to overlie the cover paper. Pressure is then applied between the upper and lower plates so as to provide a metal tight compartment. The platten is then raised to a vertical position and the metal poured into the open ended mold cavity.

It is important that the pressure brought to bear against the plates be uniform in order that the metal slug being cast therein, is of uniform thickness; for if it is not uniform the ink will not be of uniform shade when the slug is subsequently used for printing purposes.

In all casting boxes heretofore devised, the clamping pressure between the plates has not been such as to bring uniform pressure between the plates at all points, with the result that the slug cast thereby has been very irregular in thickness, sometimes even to the point of being unuseable.

It is the chief object of my invention to provide means for simultaneously and uniformly applying clamping pressure to the upper and lower plates, comprising the platten, at a number of spaced points along its sides.

Another object of my invention is to provide hydraulic means for bringing about uniform pressure at all points between the upper and lower plates.

Another object of my invention is to provide means whereby the platten is locked against

2

tilting movements when the upper and lower plates are not clamped together.

A still further object of my invention is to provide an improved pouring spout on the metal container.

A still further object of my invention is to provide a novel arrangement of the metal box, heater, and scorcher platten whereby the heat utilized for the heating of the metal may also be used for heating the scorcher platten.

A still further object of my invention is the provision of a novel scorcher platten.

The above and still further objects of my invention will become apparent from the following specification and the attached drawings.

Referring to the drawings wherein like characters indicate like parts throughout the several views:

Fig. 1 is a front perspective of my novel device showing the casting platten in a horizontal position;

Fig. 2 is a perspective illustrating the tilted metal pouring position of the casting platten;

Fig. 3 is a still further perspective view showing the lower plate in a horizontal position, locked against tilting movements; but with the upper plate in a raised position;

Fig. 4 is a vertical section taken on the line 4—4 of Fig. 5;

Fig. 5 is a vertical section taken on the line 5—5 of Fig. 4;

Fig. 6 is a sectional view taken on the line 6—6 of Fig. 4;

Fig. 7 is a sectional view taken on the line 7—7 of Fig. 6;

Fig. 8 is a fragmentary sectional view taken on the line 8—8 of Fig. 4;

Fig. 9 is a fragmentary sectional view taken on the line 9—9 of Fig. 4; and

Fig. 10 is a fragmentary sectional view taken on the line 10—10 of Fig. 4.

Referring with greater particularity to the drawings, the numeral 1 indicates a frame structure in its entirety, generally rectangular in form, and comprising laterally spaced substantially parallel side members 2, a rear end member 3, and a front end member 4. Side members 2 and end members 3 and 4 are preferably, and as shown, cast separately and secured together by bolts or the like 5. Side members 2 are generally L-shaped in form so as to provide a pair of upwardly projecting laterally spaced flanges 6 at the forward end of the frame 1. Frame 1 is shown as being supported by legs 7, one on each corner thereof.

A pair of horizontally disposed rails 8 are shown as being secured by means of bolts 9 or the like to the inside faces of side members 2 in opposed relationship. Washers 9a space rails 8 from side members 2. A casting platten made up of a lower plate 10, having a flat upper surface 11, and an upper plate 12, having a flat lower face 13, is positioned between spaced side frame members 2. Plates 10 and 12, shown as being generally rectangular in form, are of cast iron or other suitable material and are provided with a plurality of outwardly projecting reinforcing ribs 14. At the forward end of lower plate 10 are a pair of spaced upstanding flanges 15 which are secured thereto by means of threaded bolts 16. Flanges 15, as shown particularly in Fig. 4, have vertically extended slots 17. Projecting outwardly from the forward end of upper plate 12 are a pair of trunnions 18 which are adapted to project through and slide in elongated slots 17 so as to allow substantial parallelity of the plates 10 and 12, at varying spacings.

Projecting rearwardly from lower plate 10 are a pair of spaced handles 19; and projecting laterally outwardly from the rear edges of upper plate 12 are a pair of handles 20. Secured to the longitudinally extending, downwardly projecting side flanges 21 of lower plate 10, by means of bolts or the like 22, are a pair of laterally spaced castings 23. Castings 23 have outwardly projecting trunnions 24 which are equipped at their ends with rollers 25 which ride on rails 8. Rollers 25 are secured to trunnions 24 by shoulder screws 25a. Castings 23 have downwardly and rearwardly projecting arms 26.

A pair of guide arms 27 are shown as having their rear ends pivoted to the rearwardly projecting end of arms 26 (see Fig. 4). The front ends of guide arms 27 have a pivotal connection at 28 to opposing bosses 28a projecting inwardly from side members 2. Guide arms 27 in cooperation with arms 26 and trunnions 24 insure downward tilting of the forward end of the platten as it is rolled in a forward direction on rails 8. Furthermore, the guide arms 27 hold the platten against torque twisting movements as it is raised to and from the dotted line position indicated in Fig. 4. Journalled for limited rotary and up and down movements in bosses 29 are clamping rods 30 having laterally offset latch lugs or fingers 31 at their upper ends. A pair of clamping bars 32 are secured to, but spaced from the under surface of lower plate 10 by means of stud shafts 33 and adjustable wing nuts 34. Interposed between the wing nuts and under surface of bars 32, as particularly shown in Fig. 9, are washers 35. Interposed between the clamping bars 32 and the under surface of bottom plate 10 are coil springs 36.

As shown particularly in Fig. 6, clamping bars 32 are in laterally spaced parallel positions, one located forwardly with respect to trunnions 24, and one spaced rearwardly with respect to trunnions 24. The extreme outer ends of clamping bars 32 project outwardly beyond the side edges of bottom plate 10 and the clamping rods 30 are journalled in each end thereof for limited rotary and axial movements. Secured fast to the bottom ends of clamping rods 30 are collars 37. As shown in Figs. 8 and 9, the collars 37 which are secured to clamping rods 30 located forwardly of the trunnions 24, have lock lugs or fingers 38 which are laterally offset and are at approximately right angles to the latch lugs 31 carried by the upper ends of clamping rods 30. It will

be noted by reference particularly to Fig. 2 that the collars 37 positioned rearwardly of the trunnions 24, are not provided with lock lugs. It will also be observed that lock lugs 38 are adapted to overlie and rest upon the rails 8 in one position of the rotatable clamping rods 30. Carried by all four of the collars 37 are inwardly projecting laterally offset crank arms 39.

Centrally pivoted to the under surface of lower plate 10 by means of a headed bolt 40, and positioned adjacent the rear edge thereof is a lever 41. As shown, particularly in Figs. 1 and 2, lever 41 is positioned near the side edge of lower plate 10 so that its outer end terminates in a handle portion 42 laterally outwardly of plate 10 and frame 1. The inner end of lever 41 terminates beneath plate 10 approximately midway between the side edges thereof.

A pair of diverging links or rods 43 have a common pivotal connection 44 at their rear ends to the inner end of lever 41. The forward ends of rods or links 43 are pivotally connected at 45 to the two opposing crank arms 39 positioned forwardly with respect to the trunnions 24.

A pair of parallel links 46 have their forward ends pivoted at 45, the same pivot as used by the forward ends of links 43, and have their rear ends pivoted at 47 (see Figs. 6 and 4) to the crank arms 39 positioned rearwardly with respect to trunnions 24.

Secured by means of headed bolts or the like 48 to the under surface of bottom plate 10, adjacent its rear edge, is a tubular metallic casing 49 which has a reduced neck portion 50 into which is threaded a shaft 51. The outer end of shaft 51 carries a hand wheel 52. The inner end of shaft 51 has an enlarged head 53 (see Fig. 6) which abuts against a reduced metallic outer end 53a of a fluid filled master bellows 54. Bellows 54 is of the type which expands and contracts longitudinally of its axis and is provided with an internal coil spring which tends to cause it to expand to its longitudinal limits when the head 53 is in a retracted position. It will be observed that casing 49 is in approximate alignment with the lever 41 and has its reduced neck portion 50, shaft 51 and wheel 52 projecting laterally outwardly from the opposite side edge of lower plate 10. Connected to the inner end of master bellows 54, is a reduced tubular neck 55 to which is secured a conventional fill-cock 56. A tube 57 is connected between the tubular neck 55 and a central distributor 58. Radiating from distributor 58 are four pipes or tubes 59, as shown particularly in Figs. 2 and 6.

Referring now particularly to Figs. 5 and 9 it will be observed that four bellows, each bearing the number 60 are interposed between the lower plate 10 and clamping bars 32, one adjacent each of the ends thereof. Bellows 60 while somewhat smaller than the master bellows 54 are of the same general design. The upper ends of bellows 60, as shown in Figs. 7 and 9, are received in circular recesses 61 in the under face of lower plate 10 and the lower ends of bellows 60 have reduced tubular necks 62 which fit snugly into vertical openings 63 in the clamping bars 32. The outer ends of pipes or tubes 59 extend, as shown particularly in Fig. 7, through openings 64 in the opposing side edges of clamping bars 32 and make fluid tight connections with the tubular necks 62.

Projecting outwardly from one side of frame member 2, immediately below one of the upstanding flanges 6, is a gas pipe 65 on the end of which is a conventional valve 66. Valve 66 has con-

nected thereto a pipe 67 which leads to a gas source or the like, not shown. After passing through upstanding flange 6, pipe 65 is bent at right angles and extends upwardly in close proximity therewith to a point approximately midway its height, where it is fitted with an elbow 68. A perforated pipe 69 extends horizontally from elbow 68 to the opposite upstanding flange 6 where it is provided with a closed end.

Positioned immediately over the horizontal gas pipe 69 is an elongated metal melting pot 10 which is equipped at its ends with trunnions 71 which are journalled for rotation in the opposed upstanding flanges 6 adjacent their upper ends. As shown in Fig. 1, one of the trunnions 71 projects through the flange 6 and is equipped with a normally upstanding crank acting handle 72. As shown trunnions 71, upon which the metal pot rotates, are laterally offset with respect to the axis of said pot so as to cause pot 10 to normally tend to rotate in a direction opposite its spout 73. For the purpose of retaining the pot in a level condition I provide an outwardly flanged upper edge 74 which overlaps and rests upon the top edges of the upstanding flanges 6, except when the spout edge is lowered.

A scorcher platten made up of flat, matched upper and lower plates 75 and 76 are secured to the forward edges of flanges 6 by means of a pair of forwardly extending relatively elongated brackets 77 at their lower ends, and a pair of forwardly extending relatively shorter brackets 78 at their upper ends. The difference in length of the brackets 77 and 78 causes the scorcher platten to assume the inclined position illustrated in Fig. 4.

Upper and lower scorcher plates 75 and 16 are connected at their opposite edges adjacent each corner by links 79 which have pivotal connections at their opposite ends with opposite plates. One of the links 79 projects upwardly and outwardly at one end to provide a handle portion 80. It should be observed that the links 79 are angularly disposed with respect to the plane of plates 75 and 76 so that when the handle portion 80 is depressed, the links are brought into a substantially right angle position with respect thereto, and the plates are separated but retained in parallel relationship.

An important feature of the pouring spout 73 of metal box 70 is the centrally located rib or tongue 81 which causes the molten metal to spread out and be equally distributed to all parts of the mold cavity into which the metal is being poured.

Operation

As in any machine of this type, when it is desired to cast a slug, the upper and lower plates 10 and 12 comprising the platten, are first placed in the horizontal position indicated in Fig. 1.

In my novel structure the plates are then unclamped by pulling handle 42 of lever 41 toward the rear of the machine as indicated in Fig. 3, thus rotating clamping rods 30 approximately 90° to a position where the latch lugs 31 do not overlap the edges of upper plate 12. Simultaneous movement of clamping rods 30 is made possible through links 43 and 46 and their pivotal connections with crank arms 39.

At the same time that latch lugs 31 are moved so as to unlock upper plates 10 and 12, lock lugs 38 are moved into a position overlying rails 8, thus locking the forward end of the plates against pivotal movements and enabling the upper plate

12 to be opened vertically on its hinges to the position indicated in Fig. 3. It should be here mentioned that the rear end of the platten rests upon the top of rear frame member 3 so as to give it greater stability.

Prior to the use of the cardboard mat or matrix, identified by the letter A, it is customary to place the same in a scorcher platten where it is thoroughly dried. In my novel scorcher platten, which is heated by the same burner which melts the stereotype metal, see Fig. 4, it is only necessary to pull the handle 80 to the dotted line position shown in Fig. 4 so as to raise the upper plate 75 to the dotted line position there shown. The matrix is then placed 15 between the inner surfaces of the plates 75 and 76, which surfaces are normally covered with asbestos or the like, and the action of gravity forces the plates firmly together as the handle 80 is released. When the matrix A is dry, it is placed 20 on the upper surface 11 of lower plate 10. The closure forming strips or bars B are then laid around two sides and the forward end of the mat, and the cover paper C placed over 25 the top of the closure strips. Upper plate 12 is then lowered into the position indicated in Fig. 7, and handle 42 of lever 41 moved in a forward direction thereby simultaneously turning all four of the clamping rods 30 approximately 90°, in 30 which position the latch lugs 31 overlap the edges of upper plate 12, and the lock lugs 38 are swung free from a position overlying rails 8.

Prior to elevating the matrix to the metal pouring position indicated in Fig. 4 it is necessary 35 to securely clamp plates 10 and 12 together. To accomplish this with my novel device it is only necessary to turn hand wheel 52 in a direction to cause shaft 51 to move inwardly, thereby compressing bellows 54. When bellows is compressed the fluid therein is forced through pipe 57 into distributor 58, and out through radiating tubes or pipes 59 and into the bellows 60. Forcing of fluid into bellows 60 causes them to elongate and exert downward force upon clamping bars 32. 40 Downward movement of clamping bars 32 also causes downward movement of the clamping rods 30 and latch lugs 31 through rigidly attached collars 37. With the plates 10 and 12 securely locked together it is now safe to place them in 45 pouring position. This is done by merely lifting upward on handles 49 or 20.

When the metal has been poured into the mold cavity and allowed to cool sufficiently, the plates 10 and 12 are again returned to a horizontal 50 position and hand wheel 52 turned in a direction to either allow or cause master bellows 54 to expand, thereby simultaneously causing the four smaller bellows 60 to contract. Contraction of the smaller bellows, of course, releases the pressure on the clamping bars 32 and clamping rods 30. Clamping latches 31 may then be turned approximately 90° to a point where they do not overlap at the top edges of upper plate 12 in a manner above indicated. The process is completed 55 by the mere lifting of upper plate 12 on its hinge so as to remove the matrix A, the slug 82, closure forming bars or strips B, and cover plate C.

Adjustment of thumb nuts 34 so as to vary the 60 tension of coil spring 36, makes it possible to obtain such a degree of uniformity of pressure on all of the clamping rods 30, that with my novel device the slugs cast thereby do not vary in thickness more than one thousandth of an 65 inch.

With machines of this type it is often desirable and necessary to cast slugs of various thickness and for this purpose I provide a reversible seat for latch lugs 31 in the form of cross sectionally circular inserts 83 screwed into the upper face of upper plate 12 by means of Allen screws 84 or the like. Seats 83 have one segment thereof 85 of a low level and the other segment 86 of a high level. When a thick slug is to be cast, the latch lug 31 is allowed to rest on the lower segment 85 whereas if a thin slug is to be cast the seat 83 is reversed so that the latch lug 31 sits upon the higher segment 86.

What I claim is:

1. In a device of the kind described, a frame having laterally spaced walls, elongated horizontally disposed rails secured to the walls of said frame in opposed relationship, a rectangular casting platten made up of lower and upper superimposed plates, a hinged connection between said lower and upper plates, roller equipped trunnions projecting from opposite sides of said lower plate and mounting said plates for limited sliding and tilting movements on said rails, a pair of clamping rods carried by said lower plate and positioned on opposite sides thereof forwardly of said trunnions, a pair of clamping rods also carried by said lower plate and positioned on opposite sides thereof rearwardly of said trunnions, laterally offset latch lugs on the upper ends of said clamping rods, means for simultaneously turning said clamping rods to and from operative positions wherein the latch lugs carried thereby overlap the edges of the upper plate, means for simultaneously applying uniform clamping pressure to the clamping rods whereby to securely clamp said upper and lower plates together when the latch lugs are in operative position, and a lock lug carried by one of the forwardly positioned clamping rods and adapted to overlie an edge of the adjacent rail and lock said platten against tilting movements when the first mentioned latch lugs are in inoperative position.

2. In a device of the kind described, a frame having laterally spaced walls, elongated horizontally disposed rails secured to the walls of said frame in opposed relationship, a rectangular casting platten made up of lower and upper superimposed plates, a hinged connection between the forward ends of said lower and upper plates, roller equipped trunnions projecting from opposite sides of said lower plate and mounting said plates for limited sliding and tilting movements on said rails, a pair of clamping rods carried by said lower plate and positioned on opposite sides thereof, forwardly of said trunnions, a pair of clamping rods also carried by said lower plate and positioned on opposite sides thereof rearwardly of said trunnions, laterally offset latch lugs on the upper ends of said clamping rods, means for simultaneously turning said clamping rods to and from operative positions wherein the latch lugs carried thereby overlap the edges of the upper plate, hydraulic means for simultaneously applying uniform clamping pressure to the clamping rods whereby to securely clamp said upper and lower plates together when the latch lugs are in operative position, and lock lugs carried by the forwardly positioned clamping rods overlying the edges of the adjacent rails and locking the forward end of said platten against downward tilting movement only when the first mentioned latch lugs are in inoperative position.

3. In a device of the kind described, a frame, a rectangular platten comprising upper and lower hinged plates mounted on said frame, trunnions projecting from the opposite sides of said lower plate and mounting said platten for limited sliding and tilting movements in said frame, a pair of clamping rods carried by the lower plate and positioned on opposite sides thereof forwardly of said trunnions, a pair of clamping rods carried by said lower plate and positioned on opposite sides thereof rearwardly of said trunnions, latch means on said clamping rods, means for simultaneously turning all of said clamping rods to and from operative positions wherein they overlap the edges of said upper plate, a pair of transverse clamping bars carried by said lower plate and spaced from the under surface thereof, the outer ends of said clamping bars journaled the lower ends of said clamping rods for rotary and axial movements, stop collars on the lower ends of said clamping rods immediately underlying the ends of said clamping bars, a source of fluid pressure connected to said lower plate, and devices interposed between said clamping bars and said lower plate and operatively connected to receive fluid pressure from said source, whereby to clamp said plates together when said latch means is in operative position.

4. In a device of the kind described, a frame, a rectangular platten comprising upper and lower hinged plates mounted on said frame, trunnions projecting from the opposite sides of said lower plate and mounting said platten for limited sliding and tilting movements in said frame, a pair of clamping rods journaled in opposite side edges of said lower plate and positioned forwardly of said trunnions, a pair of clamping rods journaled in the opposite side edges of said lower plate and positioned rearwardly of said trunnions, latch means on said clamping rods, means for simultaneously rotating all of said clamping rods to and from operative positions wherein the latch means carried thereby overlap the edges of said upper plate, a pair of laterally spaced transverse clamping bars carried by said lower plate and spaced from the under surface thereof, the outer ends of said clamping bars journaled the lower ends of said clamping rods for rotary and axial movements, stop collars on the lower ends of said clamping rods immediately underlying said clamping bars, a master fluid pressure operated bellows connected to said lower plate, and actuating bellows interposed between said clamping bars and said lower plate and operatively connected to receive fluid pressure from said master bellows whereby to clamp said plates together when said latch means is in operative position.
